UNITED STATES PATENT OFFICE

GEORGE WILLENS, OF CHICAGO, ILLINOIS

COMBINATION CLOCK AND SIGN

Application filed February 4, 1931. Serial No. 513,345.

My invention relates to advertising, and more in particular to an advertising clock.

The principal object of the invention is the provision of a simple and relatively inexpensive form of advertising in combination with a clock.

Another object is the provision of an organization of this character, which is easily serviced.

10 Another object is the provision of a device of the character set forth which may be operated entirely from a small synchronous motor of the kind usually employed in electric clocks.

15 Another object is the provision of a device according to the preceding object, which cannot readily be broken through improper handling.

20 Another object is the provision of an advertising clock in which the advertising matter is displayed to the best advantage.

25 Other objects and features of the invention will be apparent from a consideration of the following detail description taken with the accompanying drawings, wherein

Fig. 1 is an elevational view of the device of my invention, certain of the operating parts being shown in dotted lines,

Fig. 2 is a vertical central sectional view 30 taken along the line 2—2 of Fig. 1,

Fig. 3 is a transverse sectional view taken along the line 3—3 of Fig. 1,

Fig. 4 is an enlarged sectional view showing a detail of the means for establishing connection between the drive for the advertising mechanism and the source of power therefor,

Fig. 5 is an enlarged elevational view of the mechanism shown in Fig. 4,

40 Fig. 6 is a fragmentary perspective view of a part of the operating mechanism,

Fig. 7 is a fragmentary perspective view showing some of the same mechanism as illustrated in Fig. 6, but illustrating a safety 45 feature thereof, and

Fig. 8 is a modified form of the device.

In accordance with the general features of the invention I provide a clock casing, housing a suitable clock mechanism and provided with any suitable and usual time indicating

means such as the usual dial face and moving hands. Conjointly therewith I provide in a casing one or more advertising carriers, preferably in the form of drums or cylinders on the outside of which advertising matter is 55 adapted to be displayed, the clock casing having an opening for placing in view sufficient of the advertising carrier to display the part thereof which is to be seen by the observer. In its preferred form the carrier is 60 advanced a partial rotation and then held against movement for a suitable duration of time to permit the sign to be read. The advertising carriers are driven by mechanism including a clock mechanism as a source of 65 power. The clock mechanism is preferably any usual form of small synchronous motor such as now generally used in electric clocks. I also provide certain safety and operating features for securing the proper commercial 70 operation of the advertising clock, and these features will be described hereinafter.

Referring now to Figs. 1 and 2, I provide a casing 10 with a clock face 11, which in combination with hands 12 driven by clock 75 mechanism 13 displays the proper time. Although I have not shown a clock mechanism in detail, I prefer to employ a synchronous motor with a suitable time train so that the clock may be controlled entirely by the usual commercial current frequency.

As to the advertising feature, I provide a plurality of drum carriers 14 and 16. Since in most respects the two carrier mechanisms are the same, I shall describe the mechanism in connection with 14, it being understood that except for differences which will be pointed out, the description also applies to the mechanism in connection with the carrier or drum 16.

90 The advertising drum or carrier is provided with an axial shaft 17 with projecting ends suitably secured to the casing. The drums are rotatably mounted on the shaft and are turned thereon by actuating means driven by a clock mechanism.

95 Considering first the righthand side of the shaft as shown in Fig. 3, a bearing 18 in the end wall of the drum is free to move about the shaft 17; a light weight coil spring 19 is 100

placed on the projecting end of the shaft, and frictionally engages the bearing 18 and inside surface of the casing. The purpose and functions of this spring will be explained 5 hereinafter.

As to the drive on the opposite end of the drum, a ratchet wheel 21 is secured to the drum and also acts as a bearing on the shaft 17. A lever 22 pivoted axially of the drum 10 on shaft 17 carries a pawl 23 which cooperates with teeth 22a on the ratchet wheel to drive the drum in a manner to be described.

A spacer 24 is pinned to the shaft 17 between the ratchet and lever 22 and a spacer 15 26 is disposed between the lever 22 and the outside casing. It is seen from Figs. 3 and 6 particularly, that if the lever 22 is rotated back and forth the pawl 23 will engage in 20 back of successive teeth 21a and rotate the drum one tooth position each time the lever 22 is operated. A regular ratchet action takes place in which pawl 23 rides over the top of a tooth and then drops down on the tooth 25 to drive the ratchet from the tooth on the return movement of the pawl.

In driving the lever 22, I may provide any suitable reciprocating mechanism operated by a clock mechanism. In the drawings I show a driving gear 27 meshing with and driven by 30 a gear 28 forming part of the clock mechanism. A drive rod 29 has a pivotal connection to the driving gear 27 at a point away from the axis thereof and the opposite end of the rod 29 is pivotally connected to an extension 35 of the lever 22. As Fig. 6 shows, I form a substantially right angular bend 29a in the rod 29. This provides me with an assembling means, whereby the overall length of the rod can be adjusted to meet the exact 40 conditions found in a particular clock when it is assembled. It may be said that in order to obtain a satisfactory drive from a relatively small output motor, I reduce friction by making all of the connections between the 45 moving parts as loose as possible. This means that there is considerable manufacturing tolerance and the adjustment in the driving rod by means of the bend 29a permits me to allow for the differences in the dimensions which will occur from clock to clock.

The amount of rotation imparted to the drum is determined in large part by the gear 27 and the distance away from the axis of the gear at which the rod 29 is pivoted. In 55 Figs. 4 and 5 I show means for changing the gear 27 and allowing for the adjustment which must be made if a gear of a small diameter is substituted for a gear of a large diameter and vice-versa. The gear 27 turns 60 on a stub shaft 31, which is the unthreaded shank of a bolt, the threaded portion 31a being held in a boss 32 of an adjustable mounting member. This member has a bolt-like projection 33 extending through a transverse slot 34 in the plate 36 and a nut 37 following

a lock washer 38 is tightened up on the bolt-like projections 33 to hold the mounting member in any selected position within the limits of the design.

In the ratchet drive for the drum I provide certain safety and operating features, which are of importance in the proper functioning of the device. The pawl 23 is in the form of a flat spring set at an angle in a slot 22a in the lever 22. This spring is positioned so that moving in one direction it is free to flex so as to snap over a ratchet tooth and engage behind it preparatory to driving the drum one tooth position. On the drive movement, however, the side edge of the pawl 75 engages the ratchet tooth and the strain is placed upon the pawl in a direction which resists bending. A safety precaution is made also in this construction, as shown in Fig. 7. When the advertising matter on the drums is 80 changed, the attendant may move the drum in the wrong direction and this would tend to move the lever 22 through the tooth 85 engaging the pawl and it might result in a breakage of some of the working parts, 90 for example the motor where a small synchronous motor was used. The spring pawl will bend to allow the teeth to pass in a reverse direction. A boss 21b on the ratchet wheel is of substantially the same diameter 95 as the inside diameter of the teeth. Accordingly, when the drum is then turned in the proper direction the pawl immediately moves back into its normal position as shown in Fig. 6. As far as safety features are concerned, I wish to state that I also form the drive rod 29 of a somewhat resilient spring material so that the rod can flex if too great strain is applied thereto and thus prevent 100 breakage of parts which otherwise would have to move if it were not for the flexing of the drive rod. In order to equalize the work performed by the clock mechanism, I form the lever 22 with a relatively long extension 22b, which functions as a counter-weight to balance the load. With the construction shown, the drum is driven on the downward movement of the rod 29 and on the return movement upwardly the pawl 23 engages behind another tooth, preparatory to 105 driving the drum again one forward position. The weight at 22b causes some additional work to be performed by the motor on the up-stroke of the rod 29, but on the down-stroke the weight 22b functions to assist in 110 the turning of the advertising drum.

Where a plurality of drums are employed, the drive is from one drum to another. I show in Fig. 2 a drive shaft 129, which is pivotally connected to the top lever 22 to be driven thereby, but connects to the bottom lever 22 115 in substantially the same way as described in connection with the top drum.

Although the drum is turned relatively slowly, and although it is relatively light in 120 125 130

weight, it possesses some momentum when the driving mechanism has reached the end of its driving movement and it is desired to prevent an overrunning of the drum, which might display the advertising matter out of position.

5 The spring 19 places just enough friction on the drum to prevent overrunning. I wish to avoid excessive friction, of course, because the mechanism which drives the drum is relatively limited in power and too much friction would place too great a load on it. Besides securing this result, the spring 19 also functions as a spacer in one direction. In addition, when the pawl 23 assumes the position shown in Fig. 7, (this is only an emergency position) the entire drum may be forced over against the spring 19 as much as a quarter of an inch as the spring pawl is again returning to position.

10 I may employ any suitable construction and any suitable display features in connection therewith. I use, however, in the embodiment shown a pair of end discs 41 made of relatively thin metal and a paper board 15 cylinder 42, which the formed edges of the discs engage to produce a very light weight drum. At regularly spaced intervals narrow fibre board strips 43 are stapled to the cylinder 42 in such a way that the edges 20 thereof are allowed to project up at a slight angle throughout the length of the drum. Advertising cards 44, which are preferably relatively thin, engage under the strips in the manner shown. (Fig. 2.) The advertising 25 matter on these cards is visible through openings 46 in the clock casing. The opening should be just wide enough as compared with the card so that all of the advertising matter on any one card is displayed to view, but advertising matter on adjacent cards is entirely 30 concealed. It is of course obvious that there must be a tooth 21a for each card space 44, as each time the drum is turned one tooth position it is also turned one card position.

35 In the design and operation of the clock there are some features which should appear clear from the preceding description, but in order that those skilled in the art may have no misunderstanding of all the features of 40 the invention, some of these details will be explained more fully.

The throw or amplitude of movement of the rod 29 is determined by the distance off center at which it is pivotally attached to the 45 gear 27. If its movement up and down is equivalent to the width of one tooth, then it will require the same amount of time for the drum to turn from one position to another as the time the drum will stand in one position after being turned. In other words, the display period and the moving period 50 will correspond. But the rod 29 may move just slightly less than the width of two teeth; that is, just enough to avoid engaging behind the second tooth during the dwell of

the drum. Then the display period will be almost three times as long as the movement period. It is quite clear that by changing the speed of drive by substituting a larger or smaller wheel 27, or by changing the location of the pivot point between the drive rod 29 and the gear 27, or by other obvious adjustments substantially any driving sequence desired or any timing scheme within the limitations of the design can be obtained. 75

The clock is intended for use in public places such as small theatre lobbies, retail establishments and other places where the public is accustomed to looking for the time. The advertising matter will be any that will be in keeping with the particular requirements present or the desirability thereof. For example, where the clock is used in the lobby of a theatre, it could advertise coming attractions or it could advertise the wares 80 of local merchants which would be used in relatively smaller communities. A grocery store or drug store can advertise "specials" of the day or week. For the advertising signs, an ordinary fairly stiff grade of paper can 85 be used. It can either be printed or hand lettered, although of course the best advertising results are obtained with nicely colored, printed signs. The cheapness of the sign and the ease and quickness with which it can be 90 changed, render the advertising clock ideally suited for the purpose for which it is designed. 95

Another feature and advantage of the drum driving means has to do in aiding the synchronous motor to keep the proper time speed. When the pawl engages the ratchet wheel on the drive stroke of the rod 29, there is just enough give to enable the motor to overcome the inertia of the drum without losing any of its forward speed. I have found that when a positive load is placed on the motor at spaced intervals, the motor may lose the equivalent of one current cycle, thereby gradually losing time. The spring connections, including the drive rod, and principally the spring pawl overcome this tendency. 110

What I claim as new and desire to protect by Letters Patent of the United States is:

1. In an advertising clock, a clock mechanism, a pivotally supported drum, a ratchet gear carried by the drum, a lever pivoted axially of the drum, a pawl carried by the lever and engaging said ratchet wheel, a rod having one end pivotally connected to the lever, means operable by the clock mechanism for reciprocating said rod, and safety means for preventing breaking of the clock mechanism when the drum is turned against the holding action of said pawl. 125

2. In an advertising clock, a clock mechanism, a pivotally supported drum, a ratchet gear carried by the drum, a lever pivoted axially of the drum, a pawl carried by the 130

- lever and engaging said ratchet wheel, a rod having one end pivotally connected to the lever, a gear wheel driven by the clock mechanism, means for forming a connection between the rod and gear wheel to cause a reciprocation of the rod, and mounting means for the gear wheel to permit replacement or adjustment thereof to modify the reciprocating characteristics thereof.
- 10 3. In an advertising clock, a clock mechanism, a drum having a pair of axial pivot members, a ratchet wheel at one pivot, a pawl engaging the ratchet wheel, means driven by the clock mechanism for reciprocating the pawl a distance equal to at least one tooth interval of the ratchet whereby the drum is intermittently advanced, and a coil spring mounted at the other pivot and frictionally engaging the drum, said spring arresting movement of the drum when released by the pawl, and allowing end movement of the drum to aid in releasing the pawl when the drum is turned by hand against the holding action of the pawl.
- 15 4. In an advertising clock, a clock mechanism, a drum having a pair of axial pivot members, a ratchet wheel at one pivot, a pawl engaging the ratchet wheel, means driven by the clock mechanism for reciprocating the pawl a distance equal to at least one tooth interval of the ratchet, whereby the drum is intermittently advanced, and a coil spring mounted at the other pivot and frictionally engaging the drum, said spring arresting movement of the drum when released by the pawl, and allowing end movement of the drum to aid in releasing the pawl when the drum is turned by hand against the holding action of the pawl, said pawl formed of
- 20 spring steel and set at an angle to flex away from the ratchet wheel when the drum is so turned by hand.
- 25 5. In an advertising clock, a clock mechanism, a pivotally supported drum, a ratchet gear carried by the drum, a lever pivoted axially of the drum, a pawl carried by the lever and engaging said ratchet wheel, a rod having one end pivotally connected to the lever, means operable by the clock mechanism for reciprocating said rod, said rod being formed of relatively small gauge spring steel, adequately strong to drive the drum in normal operation, but flexing when the drum is turned in a reverse direction, thereby avoiding placing a breaking strain on the parts of the clock mechanism.
- 30 6. In an advertising clock, a clock mechanism, a pivotally supported drum, a ratchet gear carried by the drum, a lever pivoted axially of the drum, a pawl carried by the lever and engaging said ratchet wheel, a rod having one end pivotally connected to the lever, and means operable by the clock mechanism for reciprocating said rod, said lever being counterweighted to equalize the load
- 35 on the motor during the reciprocating cycle of said rod.
7. In an advertising clock, a clock mechanism, a pivotally supported drum, a ratchet gear carried by the drum, a lever pivoted axially of the drum, a pawl carried by the lever and engaging said ratchet wheel, a rod having one end pivotally connected to the lever, means operable by the clock mechanism for reciprocating said rod, a second pivotally mounted drum, a ratchet wheel secured thereto, a pivoted lever having a pawl engaging said ratchet wheel, and a rod having a pivotal connection to said lever and to said first mentioned lever, whereby reciprocating movement of the first mentioned rod is imparted to the second mentioned rod and the two drums are rotated in unison.
- 40 In witness whereof I hereunto subscribe my name this 16th day of January, 1931.
- GEORGE WILLENS.
